(57) **CLAIM**

The ornamental design for a thermometer as shown and described.

DESCRIPTION

FIG. 1 is a perspective view of a thermometer showing our new design, shown from the top, front, and right side; FIG. 2 is another perspective view thereof, shown from the top, front, and right side;

FIG. 3 is another perspective view thereof, shown from the bottom, rear, and left side;

FIG. 4 is a rear elevation view thereof;

FIG. 5 is a front elevation view thereof;

FIG. 6 is a left side elevation view thereof, the right side elevation view being a mirror image thereof;

FIG. 7 is a top plan view thereof; and,

FIG. 8 is a bottom plan view thereof.

The evenly spaced broken lines depict features of the thermometer that form no part of the claimed design. The dash-dot-dash broken lines illustrate and define boundaries of the claimed design and form no part of the claimed design.

1 Claim, 6 Drawing Sheets
